UNITED STATES PATENT OFFICE

HENDRIK STUKART, OF LA PORTE, INDIANA, ASSIGNOR TO U. S. SLICING MACHINE COMPANY, OF LA PORTE, INDIANA, A CORPORATION OF INDIANA

BREAD SLICING MACHINE

Application filed January 30, 1925. Serial No. 5,681.

This invention relates to bread slicing machines similar to that shown in my prior application, Serial No. 683,547, filed December 23, 1923.

5 The invention has for its object the provision of a bread slicer which shall be of improved construction and operation, and in which a more direct drive is provided than that shown in my prior application, and in 10 which improved means is provided for feeding the bread to the slicing knife.

The invention is exemplified in the combination and arrangement of parts shown in the accompanying drawings and described 15 in the following specification, and it is more particularly pointed out in the appended claims.

In the drawings—

Fig. 1 is a front elevation, with parts in 20 section, showing one embodiment of the present invention;

Fig. 2 is a section on line 2—2 of Fig. 1;

Fig. 3 is a section on line 3—3 of Fig. 1; and

25 Fig. 4 is a section on line 4—4 of Fig. 1.

The slicing machine comprises a front bracket 10 and a rear bracket 11 connected by rods 12 and 13 and a sleeve 14. A bread trough or slideway 15 extends from the rear 30 to the front bracket and is supported by a bar 16 connected to the brackets at their ends. A shaft 17 is enclosed in the sleeve 14 and journaled in the brackets. A drive wheel 18 is mounted on the rear end of the shaft 17 35 and a yoke 19 is secured to the forward end of the shaft. The yoke 19 carries an arm 20 which is journaled on a sleeve 21 secured to the bracket 10 in spaced relation but in axial alignment with the bearing for the front end of the shaft 17. The arm 20 is provided with a bearing 22 having eccentric bushings 23 therein in which a spindle 24 is rotatably mounted. The spindle 24 carries a slicing knife 25 fixed to the rear end thereof and a sprocket wheel 26 is formed on the spindle 40 adjacent the rear face of the slicing knife.

The bearing 22 is provided with a lock bolt 27 for holding the eccentric bushings 23 in adjusted positions. By releasing the bolt 50 27 and shifting the bushings 23 the axis of

the spindle 24 may be shifted to adjust the tension in the sprocket chain passing over the sprocket wheel 26. A second sprocket 28 is fixed to a spindle 29 extending through the sleeve 21 and rotatably mounted therein. A hand crank 30 is fixed to the forward end of the spindle 29 and is provided with a stop 31 by means of which the hand crank may be held against rotation. This will lock the sprocket wheel 28 in fixed position so that 55 when the yoke 19 is rotated by the shaft 17 the sprocket chain connecting the wheels 26 and 28 will impart a rotary movement to the knife 25 in addition to its revolution about the axis of the shaft 17. A lock pin 32 is provided on the bracket 11 for locking the hand wheel 18 against rotation. It will be apparent that by causing the lock pin 32 to engage an opening 33 in the drive wheel 18 the arm 20 may be locked in its uppermost position. 60 The handle 34 for the hand crank 30 may then be rotated into the broken line positions shown in Fig. 1 which will release the hand crank and permit rotation of the sprocket wheel 28 thereby. This rotation will drive 65 the knife 25 on a fixed axis.

A removable cover 36 is provided for the upper portion of the casing which encloses the knife 25. By removing the cover 36 the sharpener 37 may be brought into engagement with the edge of the knife for sharpening the knife while being rotated by the hand crank. A second opening 38 is provided in the drive wheel 18 diametrically opposite the opening 33. This will permit the knife to 75 be locked in its lowermost position to facilitate cleaning.

The loaf of bread 39 or other article to be sliced is held by a follower 40 having a front plate 41 against which the rear end of the loaf is placed. A tooth carrier 43 is pivotally mounted at 44 on the follower 40 and is provided with a plurality of curved teeth 45 which project through slots 46 in the upper edge of the front plate 41. A spring 47 normally urges the teeth 45 into their operative position to engage the loaf 39, as shown in Fig. 1. Since the teeth are curved, the spring 47 moves the teeth in a direction not only toward the portion of the clamp upon which 80 85 90 95 100

the substance rests, but also toward the plate 41 or abutment against which the end of the loaf is held. A hand piece 48 extends upwardly from the tooth carrier 43 in position 5 to be engaged by the thumb of the operator when it is desired to release the loaf or to return the follower to its initial position at the rear end of the bread slide 15. The follower 40 is supported on a bracket 49 secured by 10 screws 50 to a sleeve 51 slidably mounted on the rod 12. A handle 52 is secured to the sleeve 51 for moving the sleeve 51 along the rod. A bell crank lever 53 is pivotally connected at 54 to the sleeve 51 and is provided 15 with a downwardly extending fork 55 which engages a pin 56 in the end of a slide rod 57.

A housing 58 extends downwardly from the sleeve 51 for supporting the slide rod 57 and a spring 59 is mounted in the housing 20 58 for normally urging the rod 57 to the left, as viewed in Fig. 3. A feed screw 60 is journaled in the end brackets 10 and 11 and is intermittently rotated for feeding the follower 40 toward the slicing knife. The rod 25 57 is provided with a toothed end 61 for engaging the threads on the screw 60. A bracket 62 extends inwardly from the housing 58 and is provided with a frictional contact member 63 arranged in position to engage the 30 lower face of the bar 16. The member 63 may be made of fibre or other suitable material.

It will be apparent that the spring pressure 35 on the teeth 45 in forcing the teeth into the loaf will tend to lift the follower 40 away from the runway 15. The contact member 63 will counteract this force and retain the follower in its proper position on the runway. The contact member 63 also provides frictional engagement to prevent overthrow of 40 the feeding mechanism at the end of a feeding operation, thus insuring uniformity in the slices produced.

The screw 60 is provided with a one-way 45 drive 64 at its rear end to which a link 65 is pivotally connected. The upper end of the link 65 is pivoted at 66 to a sleeve 67 supported on a rod 68. The rod 68 is secured to a bracket pivoted at 70 on the rear frame 50 member 11. The bracket 69 is provided with a cam roller 71 which engages a cam 72 on the drive wheel 18. It will be noted from Fig. 1 that the cam roller 71 is disposed with 55 in a continuous circular flange 73 on the drive wheel 18 so that if the cam should be thrown outwardly by centrifugal action it will engage the smooth inner surface of the continuous flange 73 and there will be no danger of any of the parts jamming to stop the machine or break the mechanism. Such action 60 on the part of the cam roller 71 is normally prevented, however, by the spring 74 which holds the cam roller 71 against the drive surface of the cam 72. It will be seen that at 65 each oscillation of the link 64 the screw 60

will be rotated to feed the follower 40 toward the slicing knife. The amount of rotation may be regulated by the sleeve 67 along the rod 68.

As will be seen from Fig. 2, the front portion of the rear bracket 11 is left entirely open so as to provide space for the operator's hand when the follower 40 is moved backwardly to its rearmost position. This permits the follower to be slid to the right, 75 as viewed in Fig. 1, a sufficient amount to utilize substantially the entire length of the slideway 15 for long loaves of bread. When the follower is moved to its rearmost position the toothed member 61 will be brought 80 into registration with the end portion of the bearing 75 in which the rear end of the screw 60 is journaled. This will prevent the toothed member 61 from engaging the threads of the screw so that rotation of the drive wheel 18 will not feed the follower forwardly, thus allowing opportunity to secure a new loaf against the face of the plate 41. If it should be desired to adjust the parts so that the follower will immediately begin its forward movement a stop bar 76 is provided 85 which may be swung into position to engage the end of the rod 12 so that the sleeve 51 will engage the stop bar and thus arrest the rearward movement of the follower in such 90 position that the toothed member 61 will miss the bearing 75 and engage the threads of the screw 60.

I claim:—

1. A bread slicing machine comprising a 100 pair of spaced upright brackets, a slideway connecting said brackets, and slicing mechanism supported at one end of said slideway while the bracket at the opposite end of said slideway is open at one side of said slideway 105 to permit free movement of the operator's hand in adjusting material on said slideway.

2. A slicing machine comprising a pair 110 of spaced supports, a slideway connecting said supports, said slideway having a side wall at one side thereof but having the opposite side thereof open, and slicing mechanism disposed adjacent one of said brackets while the other of said brackets extends past said slideway on the side thereof adjacent said side wall but is open at the opposite side of said slideway to permit free movement of the operator's hand.

3. A slicing machine comprising a pair of 115 spaced brackets, a slideway connecting said brackets, a drive shaft arranged above said slideway and journaled in said brackets, and slicing mechanism supported on one of said brackets, the other of said brackets being provided with a supporting member at one side 120 of said slideway only.

4. Slicing mechanism comprising a slide- 125 way, a guide rod at one side of said slideway, a sleeve slidably mounted on said guide rod, and a bracket connected with said sleeve and 130

arranged to engage the lower side of said slideway.

5. A slicing machine comprising a slide-way, a guide rod at one side of said slideway, a sleeve mounted on said guide rod, a follower connected with said sleeve and disposed over said slideway, a feed screw, means connected with said sleeve for engaging said feed screw, and a frictional device connected with said sleeve and arranged to engage the lower face of said slideway.

6. A slicing machine comprising a sheet metal slideway, a supporting bar extending longitudinally of said slideway and secured 15 to the interior face thereof, a follower arranged to travel along said slideway, and a frictional device connected with said follower and arranged to engage said supporting bar.

7. A slicing machine comprising a slideway 20 having one side thereof open, a guide rod disposed adjacent said open side, a feed screw arranged beneath said slideway, a sleeve on said guide rod, a follower connected with said sleeve and disposed over said slideway, a 25 spring actuated toothed member connected with said sleeve for engaging said feed screw, a handle for releasing said toothed member, and a bracket connected with said sleeve and projecting beneath said slideway for engaging 30 the lower face of said slideway.

8. A slicing machine comprising a slide-way, a follower arranged to travel along said slideway, a feed screw for moving said follower along said slideway, a spring actuated 35 member for engaging said feed screw, said follower being movable into one position at the extremity of its range of travel in which said spring actuated member is prevented from engaging said feed screw, and means 40 for preventing said follower from being moved to said position.

9. A slicing machine comprising a slide-way, a follower for moving material along said slideway, a feed screw for actuating 45 said follower, means connected with said follower for engaging said feed screw, and means which may be set at the will of the operator for either permitting or preventing operative connection between said follower 50 and feed screw when said follower is moved to its extreme position.

10. A slicing machine comprising a slide-way for supporting the substance to be sliced, a member carrying a plurality of teeth 55 spring pressed towards said slideway, means for guiding said member in the direction of said slideway, and means operatively connected with said member and extending under said slideway from the side on which 60 said member is arranged and having a portion thereof in engagement with the under side of said slideway to prevent movement of said member away from said slideway.

11. A slicing machine comprising a sub-65 stance support, a work holder for moving a

substance along said support, feeding means for said work holder, a slicing knife, means for retracting said work holder to an extreme position away from said knife in which said feeding means is inoperative, and a 70 stop movable into operative position at the will of the operator for preventing movement of said work holder to said extreme position.

12. A slicing machine comprising a slicing 75 knife, a work holder for moving the substance to be sliced towards the slicing knife, a feed screw and a feed nut for feeding said work holder toward the slicing knife, means normally urging said feed nut and said feed screw into engagement with each other, means for withdrawing said feed nut from engagement with said feed screw to permit the operator to move said work holder to an extreme position away from said knife, 80 an abutment arranged so as to be interposed between said feed nut and said feed screw in said extreme position, and a movable stop member movable by the operator into a position to prevent movement of said work 85 holder to a position in which said abutment is interposed between said feed nut and feed screw.

13. A slicing machine comprising a knife mounted to rotate about its own axis and an 90 axis eccentric to its own axis, driving gears concentrically mounted with reference to said axes, means for operatively connecting said driving gears, means operable by the operator for holding one of said gears stationary or for rotating said gear depending upon the movement which it is desired to give to said slicing knife, said means comprising an arm, and a handle pivoted to said arm and carrying a stop thereon adapted to 95 cooperate with a rigid stationary abutment when said handle is in one position and to be out of engagement with said abutment when said handle is in another position of adjustment.

14. A slicing machine comprising a substance support, a work holder for moving a substance along said support, a feeding means for said work holder, a slicing knife, means for retracting said work holder to an extreme position away from said knife, said feeding means comprising a feed screw and a follower and being rendered totally inoperative by the movement of said work holder to said extreme position, and a stop 115 movable into operative position at the will of the operator for preventing movement of said work holder to said extreme position.

In testimony whereof I have signed my name to this specification on this 27th day of January, A. D. 1925.

HENDRIK STUKART.
